UNITED STATES PATENT OFFICE

RALPH P. HACKET, OF ALLENTOWN, PENNSYLVANIA

ATTACHMENT FOR SEWING MACHINES

Application filed June 3, 1932. Serial No. 615,191.

This invention relates to attachments for sewing machines, and it has for its principal object the provision of a button sewing device which, by the substitution of a single part and the adjustment of a single element, setting additional mechanism into action, is converted into a button hole stitching apparatus.

Other objects of the invention will appear 10 as the following description of a preferred and practical embodiment thereof proceeds.

In the drawings which accompany and form a part of the following specification, and throughout the several figures of which the 15 same characters of reference have been employed to designate identical parts,

Figure 1 is a side elevation of the convertible button sewing and button hole stitching device;

20 Figure 2 is a side elevation of the same showing the reverse side;

Figure 3 is a plan view of the same;

Figure 4 is a bottom view with parts removed so that the construction of the cams 25 is disclosed;

Figure 5 is a longitudinal vertical section through the device;

Figure 6 is a view similar to Figure 1 showing the device converted into a button hole 30 sewing attachment;

Figure 7 is a bottom plan view of the cloth-shifting plate shown in Figure 6;

Figure 8 is a side view showing the friction clutch in disassembled state; and

35 Figure 9 is a diagram illustrating the motions imparted to the cloth incident to the button hole stitching operation.

Before advertizing to a description in detail 40 of the several figures, it may be stated that, assuming the needle of the sewing machine repeats its oscillatory movements in the same path, provision must be made in stitching the button hole for moving the cloth in the following directions, referring to Figure 9; (a) lengthwise along one side of the button hole in one direction; (b) cross-wise at one end of the button hole; (c) lengthwise of the other side of the button hole to the opposite end of the latter and then, (d) transversely across 45 the end in the opposite direction.

While the goods is being moved lengthwise of the button hole it must be given a repeated side to side motion (e) of less amplitude than the transverse movements (b) and (d) for the purpose of forming the stitch. All this 55 is, of course, well known.

Now, in sewing on a button, the cloth-shifting element is removed so that the cloth remains stationary, while a button cup is substituted therefor, and by inhibiting the operation of that part of the mechanism which produces reciprocatory movement of the cloth and the transverse movement of major amplitude which takes place at both extremes of the reciprocatory movement, the button cup 60 is limited to the transverse movements of minor amplitude which will take place repeatedly over the same path in view of the absence of longitudinal movement.

70 Referring now in detail to the several figures, the numeral 1 represents the body which is provided at one end with a collar 2 open at its forward end so as to constitute a pair of jaws 3 and 4 adapted to encompass the pressure bar, not shown, of the sewing machine and to be secured thereto by a pair of jam screws 5 and 6. It is obvious therefore, that the body 1 when in place, will be rigid and immovable, excepting that it can be 75 raised or lowered when the pressure bar is 80 elevated or depressed.

A carriage 7 is mounted on the underside of the body 1, said carriage being provided with a longitudinal slot 8, Figure 5 through which extends the guide studs 9 and 10, said studs screwing into sockets formed at the lower ends of the bolts 11 and 12 which pass through the body from bottom to top. The shanks of the studs 9 and 10 serve as spacers 85 to prevent the studs tightening against the carriage, so that the latter is reciprocable longitudinally along the bottom of the body 1.

90 Since provision must be made also for oscillatory movement of the carriage with respect to the body, the slot 8 is necessarily made considerably wider than the diameter of the studs 9 and 10. Consequently, the slot 95 8 cannot act as a guide for the reciprocatory movement of the carriage, and in order to ensure that it shall reciprocate rectilinearly, 100

a guide plate 18 is provided having slots 14 and 15 which closely fit the studs 9 and 10 laterally, said plate being retained between lugs 16 and 17, struck up from said carriage.

5 The forward end of the carriage is provided with the button cup 18 comprising a transverse member 19 detachably secured to the bifurcated ends 20 and 21 of the carriage and having on its lower face a frusto-conical 10 cup-shaped element 22.

The body 1 is hollow forming a casing for enclosing the mechanism which determines the oscillatory and reciprocatory movement of the carriage. This mechanism comprises 15

two cams, 23 and 24. These cams are in the form of cylinders and mounted on the respective shafts 25 and 26 which are journaled in the sides of the casing or body 1. The cams have cam grooves in their peripheral faces.

20 The cam 23 has an undulating cam groove which determines the oscillatory movement of minor amplitude, forming the stitch, both in stitching the button hole and sewing on the button. The cam 24 has only one single

25 jog to a complete revolution, this being to provide the oscillatory movement of major amplitude which happens at each end of the button hole.

The means for imparting rotation to the 30 cams is a lever 27 oscillating in a vertical plane and having a bifurcated end 28 adapted to embrace a screw, not shown, but which extends from the side of the needle bar of the sewing machine.

As the needle bar reciprocates in the operation of the sewing machine, the lever 27 oscillates and through a pawl 29 and ratchet 30 it imparts step by step movement to the cam 23. Said cam imparts oscillatory movement of minor am-

40 plitude to the carriage by means of a lever 31 pivoted at 32 and having a roller 33 ex-

45 tending into the cam groove 34. The undulations of said cam groove produce oscillation of the lever 31, said lever is provided with a slot 35 and in said slot plays a pin 36 having a collar 37 playing in a slot 38 formed in the carriage 7. Oscillation of the lever 31 thus produces a transverse oscillation of the carriage 7 about its pivotal connection

50 constituted by the stud 9.

Step by step movement is imparted to the cam 24 by means of a shoulder 39 formed on the lever 27 which depresses the arm 40 of a lever 41, the latter constituting an element 55 of a uni-directional clutch, the parts of which are shown in spread relation in Figure 8. The clutch consists of a disk 42 having a non-round aperture 43 which receives a similarly shaped end of the shaft 26 so that

60 the disk 42 is thus fixed to said shaft. The disk 42 seats freely in a circular aperture 44 formed in a loose member 45. The member 45 is mounted loosely against the lever 41 with a boss 46 on said lever extending 65 through the recess 47 formed on said loose

member. The front side 48 of the boss 46 is preferably formed with the curvature of the aperture 44 and the back side of the boss 46 has a circular curvature which corresponds to the circular curvature of the recess 47. A washer 49 rests against the clutch assembly and a thumb nut 50 screws on the end of the shaft 26 and holds the washer against the clutch assembly. A light spiral spring 51 draws down on one end of the lever, normally throwing the arm 40 up against an adjustable stop 53.

When the lever 27 is drawn upwardly by the needle bar, the shoulder 39 presses down on the arm 40, oscillating the lever 41 and causing the upper corner of the boss 46 to press outwardly against the periphery of the disk 42, binding the disk in the aperture 44 and causing the lever 41, the disk 42 and the shaft 25 which carries the cam 24, to oscillate as a whole. When the needle bar goes down, the lever 27 is pushed downwardly, raising the shoulder 39 and permitting the lever 41 to oscillate in the opposite di-

rection under the urge of the spring 51. This withdraws the upper corner of the boss 46 away from the aperture 44 causing the curved surface 48 of the boss to coincide with the circumference of said aperture so that the disk 42 no longer binds within said aperture, enabling the upward movement of the arm 40 without reverse movement of the shaft 25 and cam 24.

The cam 24 is connected with the carriage 7 by means of a lever 57 similar to the lever 31 having an arm carrying a roller 58 which plays within the groove 59 of the cam 24, said lever being slotted as at 60 and pro-

vided with a pin 61 playing in the slot 60 and having at its other end a roller which plays within the slot 38.

The opposite end of the shaft 25 is provided with a segmental gear 62, the teeth of which do not occupy substantially more than one-third of its circumference. Said gear is surrounded by a closed yoke 63 having an elongated slot 64, the sides of which have racks 65 and 66 adapted to be engaged by the gear teeth 62. The ends 67 and 68 of the slot are smooth and adapted to receive the smooth part of the gear 62. In the step by step actuation of the cam shaft 25, the gear 62 rotates, meshing first with the rack 65 to produce reciprocatory motion of the yoke in one direction, then meshing with the teeth of the rack 66, producing reciprocatory movement of the yoke in the opposite direction. The yoke is provided with an ex-

110 tension 69 pivotally connected to a link 70. Said link is pivotally mounted at one end in an extension 71 of the body 1, the free end of the link 70 being slotted. A pin 72 passes through the slot in said link and through a slotted member 73 upstanding from the carriage 7. By means of this

115

120

125

130

slotted connection between the carriage and link, reciprocatory movement of the yoke in one direction or the other imparts reciprocatory movement to said carriage.

5 By shifting the pin 72 in the slots in said link and slotted member, the extent of the reciprocatory movement of the carriage may be varied. By shifting the pins 36 and 61 relative to the slots in the levers 31 and 57 respectively, the oscillatory movements of the carriage both of major and minor amplitude, may also be varied.

The stop 53 is eccentric, and held in any position of adjustment by means of the jam screw 74 and by loosening this jam screw and shifting the eccentric, the lever 40 may be moved closer or farther away from the shoulder 39 on the lever 27. By diminishing the normal distance between the arm 40 and 20 the shoulder 39, the latter is rocked through an oscillation of greater amplitude and the angular displacement of the shaft 26 is correspondingly increased. This serves as a means for adjusting the spacing apart of the 25 stitches along the sides of the button hole and for determining the length of the row of stitches on each side of the button hole. In other words, for a short button hole the eccentric stop 53 will be adjusted to produce 30 a relatively great space between the arm 40 and the shoulder 39. For a long button hole an adjustment will be made so as to produce a relatively small distance normally between said arm and said shoulder.

35 When a button hole is to be stitched, the plate 19 together with the button holding cup 22 is removed from the carriage 7 and the rectangular cloth-engaging foot 75 is substituted therefor. This foot will partake 40 of each of the movements provided for the carriage, and as above described, and the cloth will be moved accordingly, forming a row of stitches along one side of the button hole, providing a cross-over stitch at the 45 end of the button hole, sewing a row of stitches along the opposite side of the button hole and providing a cross-over stitch in the opposite direction at the opposite end of the button hole.

50 It is obvious that when a button is to be sewn and the cloth-engaging foot 75 has been replaced by the button cup 22, the reciprocatory movement of the carriage and the transverse movement of major amplitude 55 which produces the cross-over stitch at the ends of the button hole, may be inhibited by preventing the oscillation of the lever 41 which communicates motion from the cam 23 to the cam shaft 25 of the cam 24.

60 In order to accomplish the inhibition of these undesired movements, the eccentricity of the stop 53 is made such that when it is adjusted so that its maximum throw is normal to the arm 40 of the lever 41, said arm is 65 placed at such a distance from the shoulder

39 as not to be engaged at all by said shoulder when the lever 27 oscillates. Under these circumstances, only the cam 23 will be operated, producing through the intermediary of the lever 31, the transverse oscillations of minor amplitude which will shift the button cup to the right and to the left repeatedly in the same path. The needle will therefore, pass first through one eye of the button and then through the other eye and so on repeatedly until the button is attached. Variation in the distance apart of the eyes of the buttons is compensated by shifting the pin 36 an appropriate distance leftwards or rightwards within the slot 35 of the lever 31.

70 It is thus apparent that by the mere substitution of a button holding cup for the cloth-shifting foot, and by the adjustment of the stop 53 to such an extent that the arm 40 is thrown beyond the reach of the shoulder 39, 75 the button hole stitching attachment is transformed into a button sewing device, and that to change it back again to a button hole stitching mechanism, it is only necessary to replace the button holding cup 22 by the cloth-shifting foot 75 and to adjust the eccentric stop so as to bring the arm 40 of the lever 41 again 80 within striking distance of the shoulder 39 of the lever 27.

85 While I have in the above description disclosed what I believe to be a preferred and practical embodiment of the invention, it is to be understood that the details of construction as described are merely by way of example and not to be construed as limiting the 90 scope of the invention as defined in the appended claims.

95 What I claim is:

1. Button sewing and button hole stitching attachment for sewing machines comprising 100 a body adapted to be fixedly attached to a sewing machine, and a carriage reciprocably and oscillatably mounted at the bottom of said body, a button holding element detachably connected to said carriage, means carried by said body for imparting step by step 105 reciprocatory movement to said carriage throughout a range of movement first in one direction and then the other, means for imparting oscillations of major amplitude to said carriage at the end of the range of its reciprocatory movements whereby the latter 110 movements take place in opposite directions in displaced parallel paths, means for imparting a plurality of oscillations of minor amplitude to said carriage throughout its reciprocatory movement, the means for imparting reciprocatory movement, the major oscillations and the minor oscillations functioning for the button-hole stitching operation, needle bar operated means for actuating 115 said minor oscillations imparting means, a connection between said last named means, and said means for imparting major oscillations and said means for imparting reciprocating 120 operations and said means for imparting reciprocating operations.

catory movements, and adjustable means for moving said connection out of operative relation to said major oscillation imparting means and said reciprocatory movement imparting means for inhibiting the last two named movements during the button sewing operation.

2. Button sewing and button hole stitching attachment for sewing machines as claimed in claim 1, the button holding element including a cup having an inverted frustoconical depression for receiving said button and holding it shiftably against the underlying cloth to which it is to be sewn.

15 In testimony whereof I affix my signature.
RALPH P. HACKET.
